UNITED STATES PATENT OFFICE.

WILLIAM D. STOWE, OF SCRANTON, PENNSYLVANIA.

DESIGN FOR A SIGNALING DEVICE.

53,055.

Specification for Design.

Patented Mar. 4, 1919.

Application filed December 30, 1918. Serial No. 268,991. Term of patent 14 years.

To all whom it may concern:

Be it known that I, WILLIAM D. STOWE, a citizen of the United States, residing at Scranton, in the county of Lackawanna and State of Pennsylvania, have invented a new, original, and ornamental Design for Signaling Devices, of which the following is a specification, reference being had to the accompanying drawing, forming part thereof.

The drawing is a perspective view of a signaling device showing my design.

I claim:

The ornamental design for a signaling device, substantially as shown.

In testimony whereof, I have hereunto subscribed my name.

WILLIAM D. STOWE.
